UNITED STATES PATENT OFFICE.

CHARLES NEWTON, OF BUFFALO, NEW YORK.

POWDER AND PROPELLANT FOR USE IN FIREARMS.

1,074,809.

Specification of Letters Patent.

Patented Oct. 7, 1913.

Application filed June 13, 1911. Serial No. 632,821.

To all whom it may concern:

Be it known that I, CHARLES NEWTON, a citizen of the United States of America, residing at Buffalo, in the county of Erie and 5 State of New York, have invented certain new and useful Improvements in Powders and Propellants for Use in Firearms, of which the following is a full, clear, and exact description.

10 My invention relates generally to powders and propellants for fire arms, and more particularly to powders and propellants which present an increasing burning surface after they have been ignited.

15 One of the objects of my invention has been to provide a propellant, which when placed in a fire arm, behind a projectile and ignited, shall maintain, as near as possible, a constant pressure upon the said projectile, 20 as it moves forward at an accelerated velocity.

Another object has been to provide a propellant which shall produce a given velocity of the projectile at a reduced breech 25 pressure of the fire arm in which it is used, or increase the velocity of the projectile without increasing the breech pressure.

All propellants now in use in fire arms, consist of substances so compounded as to 30 burn freely and progressively, and are made in various forms, such as cubes, cylinders, disks, perforated disks, perforated cylinders, cords, strips and many other forms, but all of the forms of propellants consist 35 of uniform substances throughout the unit.

The action of a propellant in use in fire arms is obtained through transforming a solid into a gas, through the agency of fire applied in the form of a priming. As 40 is well known, the propellant is placed within a chamber and securely inclosed except at one end, which said end is closed by a bullet shell or other projectile, which rests either in the case or in the bore of the 45 fire arm. When the propellant is ignited, it burns, develops gas and when the gas thus developed has attained a sufficient pressure to overcome the inertia of the projectile, it seats the projectile into the 50 barrel of the fire arm and moves the same forward under its pressure at a constantly accelerating velocity. As the projectile moves forward along the bore 55 of the barrel of the fire arm, it gives a constantly increasing space in which the gases generated by the combustion of the propel-

lant, are confined, and at the same time, the propellant is burning and generating still more gas which takes up the space thus furnished, but the gases which are generated 60 by the burning of the propellant are not generated rapidly enough to keep up a constant pressure at the base of the projectile, but maintains only a rapidly decreasing pressure thereon. Inasmuch as the projectile is moving with a constantly increasing velocity, in order to maintain a uniform pressure against its base, it is necessary that the propellant burn and thus develop 65 gas at a correspondingly increasing rate to 70 maintain this uniform pressure upon said projectile. This increased rate of burning has not heretofore been obtained, but on the contrary, the rate of burning of a propellant in use, has been decreased from the time 75 the projectile starts on its forward path, owing to the inability of the propellant to increase its rate of burning, the falling off in the rate of burning being due to the reduction of pressure, which in turn, is due 80 to the increased space in the bore of the fire arm which it occupies, and also to the decreasing area of the burning surface exposed, consequently the pressure on the base of the projectile falls rapidly after the said 85 projectile starts in motion.

In producing my invention, I provide a propellant which, when ignited, shall maintain a pressure upon the base of the projectile far greater, in proportion to the initial 90 pressure, than that now furnished by any known propellant. I accomplish this by increasing the rate of burning of the propellant as the forward movement of the projectile increases the space occupied by the 95 gas and thus imparts a greater velocity for a given maximum breech pressure or the same velocity now obtained at a much lower maximum pressure.

In this specification and in the appended 100 claims, the term "colloid" defines the base or substance from which the units of my propellant are formed; the term "kernel" defines a combination of two or more colloids; the term "multiple kernel" defines 105 a combination of a plurality of kernels.

My invention involves the use of the same substances as are now in use as propellants, with such modifications as may tend to alter the rate of burning thereof, as well as other 110 substances which may be made to burn progressively and particularly pertains to the

composition of the individual kernel or grain of powder, a plurality of which, combined in the manner hereinafter described, form the charge.

5 My invention further consists, particularly in using instead of a kernel or grain of uniform substance, such as is in use at the present time, of a kernel built up of two or more layers or coats made from colloids, 10 having different rates of burning and so disposed that the layers composed of the slower burning colloids either wholly or partially surround the layers of the quicker burning colloids and, the outer layers of slower burning colloids being first exposed to the flame of the primer, ignite first and either wholly or partially protect the inner layers of quicker burning colloids from the action of the flame and gas until such time as the 15 outer layers of slower burning colloids are partially or wholly burned away. The next layer, which is composed of a quicker burning colloid, is then ignited and, burning more freely, with less pressure than the slow burning outer colloids, generates gas more rapidly than would be possible with the slower burning colloids, and thus maintains a higher pressure upon the base of the projectile than can be done by using a kernel 20 composed of a single uniform colloid, in quantities which would give a far higher breech pressure. If kernels composed of a single uniform colloid were used in larger quantities, than at present, the breech pressure 25 of the fire arm in which they were used would be greatly and dangerously increased. This is because there is no form of kernel which, when burning, will give a burning surface which will increase as rapidly as the space to be occupied in the bore of the gun at the rear of the projectile, increases. This is also because, as the projectile moves forward, thus increasing the 30 space to be occupied by the gases generated, the pressure and temperature of the gases diminish, and, as a consequence, the rate of burning of the colloid in use, even with the area of burning surface unchanged, diminishes instead of increases. My invention 35 meets this difficulty by constantly providing different colloids, each quicker burning than the preceding one, so that the projectile is started in motion and passes along the bore of the gun and is propelled by the gases 40 developed by the slower burning colloid, with a minimum chamber pressure, and then is propelled by the action of the quicker burning colloids, as they successively ignite and burn, thus progressively accelerating the movement of the projectile far 45 more than could be done with the slower burning colloid used alone at any chamber pressure which would not destroy the firm arm. In the process of manufacturing these 50 colloids, I prefer to use as a base substance

nitrated cellulose, although I may use any other progressively burning substances. In the manufacture of powders having for their base nitrated cellulose, or similar substance, the colloid is capable of modification through chemical admixture or otherwise, so as to produce a propellant having different rates of burning; that is some colloids forming the propellant, will burn at a given rate under a less degree of gas 75 pressure and under a less degree of heat than others, those burning under the lesser degrees of pressure or of heat being termed "quicker burning" than those which require a greater degree of temperature or a greater degree of gas pressure to produce a given degree of speed or burning, and the terms "slow burning," "quick burning" and "quicker burning" used hereinafter, are used in this sense.

Reference is to be had to the accompanying drawings forming part of this specification, in which like letters of reference indicate like colloids, in the several views of which:

Figure 1 is a cross-sectional view of the simplest form of my invention and shows a kernel formed of two colloids, each burning at a different rate of speed. Fig. 2 is a cross-sectional view of the form of kernel shown in Fig. 1 but has an additional layer around the outside, composed of a slower burning colloid. Fig. 3 is a cross sectional view of a kernel formed of two colloids of different rates of burning and provided longitudinally through the center with a perforation. Fig. 4 is a cross-sectional view of a kernel provided with a central perforation and is composed of two colloids; the inner and outer colloid being slow burning and between these is a faster burning colloid. Fig. 5 is a vertical elevation of a kernel with a portion broken away, formed as shown in Fig. 4 and shows the ends of the same closed by means of caps formed from the slower burning colloid. Fig. 6 is a fragmental sectional view showing a modified method of capping the ends of the kernels. Fig. 7 is a cross sectional view of a perforated kernel formed from a plurality of colloids of different rates of burning. Fig. 8 is a cross sectional view of a group of perforated kernels in contact at their peripheries, each formed of different burning colloids. Fig. 9 is a conventional cross sectional view of a multiple kernel, composed of a plurality of single perforated kernels compressed together. Fig. 10 is a conventional cross sectional view of a modified form of a multiple kernel, being composed of a plurality of single perforated kernels compressed together and a slow burning colloid disposed about the whole.

In the drawings the reference letter A represents a slow burning colloid; the letter B

- B a quick burning colloid; and the letter C the quickest burning colloid. While I have shown and described but three colloids of different rates of burning, obviously I may 5 employ any number of colloids of different rates of burning or vary the proportions and thicknesses of each as may be found necessary or desirable. These kernels are preferably formed by first drawing out the colloids, arranged as desired into a cord, tube or strip and then cutting the kernels therefrom. In the larger kernels as shown in Figs. 4 and 7, the cutting is done preferably at right angles to the axes of the kernel and 10 after being cut, each kernel is provided at both ends with a cap, made of a slow burning colloid A as shown in Fig. 5. For use in smaller fire arms, where the form of kernel shown in Figs. 1 to 3 are preferable, the 15 severing of the kernels is done by a pinching process instead of a clean cut. A kernel severed in this way is shown in Fig. 6 where it will be seen that the outer or slow burning colloid A has been closed at the end by 20 pinching it off and the quick burning colloid B has closed the central perforation through the kernel. This method of capping the kernel is much cheaper for the smaller or simpler forms and it may be accomplished 25 by using round edged knives or dies which will operate periodically upon the cord or tube as it leaves the machine which forms it. All the different forms of kernels shown 30 may be capped at their ends with the slow burning colloid A, as shown in Fig. 5, and the cap may either have perforations to correspond with the perforations in the kernels, thus admitting flame freely to the inside of the kernel, or the said caps may be solid, 35 depending upon the pressure of the gas as it forces itself through into the perforation of the kernel.
- In the multiple kernel shown in Fig. 10, each single kernel thereof is formed at its 40 center with a slow burning colloid A provided with a central perforation. About this is a quick burning colloid B which is in turn surrounded by a quicker burning colloid C. Surrounding this colloid C and 45 forming the outer colloid for each single kernel, is a quick burning colloid B. These single kernels are now compressed together and the whole surrounded by a slow burning colloid A. When this form of multiple kernel 50 is ignited, the colloid A surrounding the entire kernel and also the colloid A lining the perforations through the single kernels ignites first and when this is burned through, the colloid B, which forms the outer layer 55 of the individual kernels and the second layer around the perforation ignites and the multiple kernel separates into its several constituent parts, thus greatly and rapidly 60 increasing the burning surface. In placing these single kernels together to make the 65 multiple kernel like that shown in Figs. 3 and 10, a thin film of some quick burning substance may be used between the single kernels where they are in contact to insure the prompt separation of the same as soon 70 as the outer surrounding colloid A is consumed.
- For convenience in the drawings, I have shown the kernels of cylindrical form, but, obviously, they may be made in any of the 75 various forms such as cubes, cylinders, disks, perforated disks, perforated cylinders, cords, or strips or in any other combination of layers of colloids, without departing from the spirit of my invention, and I do not wish 80 to be limited to the exact forms herein shown and described.
- Having thus described my invention, what I claim is:
1. As a new article of manufacture, a propellant kernel consisting of a perforated quick burning colloid protected on its exposed surfaces by one or more layers of slow burning colloids so disposed that each layer of slower burning colloid surrounds 90 one which is quicker burning than itself. 85
  2. As a new article of manufacture, a propellant kernel consisting of a perforated quick burning colloid protected on its exposed surfaces by one or more layers of slow 95 burning colloids so disposed that each layer of slower burning colloid surrounds one which is quicker burning than itself, and end closures formed of a slow burning substance, whereby the quick burning colloids are protected until the outer layer of slower burning colloid shall be partially or wholly 100 burned away.
  3. As a new article of manufacture, a perforated propellant kernel comprising a plurality of layers of colloids having different rates of burning, said layers being so disposed that those forming the exterior surface of the kernel and the interior surface of the perforation are slowest burning and each successive layer from such surfaces toward the center of the web of the kernel being composed of a more rapid burning colloid than the one which envelops it. 105
  4. As a new article of manufacture, a perforated propellant kernel comprising a plurality of layers of colloids having different rates of burning, said layers being so disposed that those forming the exterior surface of the kernel and the interior surface 110 of the perforation are slowest burning and each successive layer from such surfaces toward the center of the web of the kernel being composed of a more rapid burning colloid than the one which envelops it, and 115 the whole protected at the ends from the flame by the application of a slow burning substance to retard the rate of burning at the ends.
  5. As a new article of manufacture, a pro- 120

pellaut kernel, having a central perforated slow burning colloid, a quick burning colloid surrounding said slow burning colloid and a slow burning colloid surrounding said quick burning colloid.

6. As a new article of manufacture, a propellant kernel, having a central perforated slow burning colloid, a quick burning colloid surrounding said central slow burning colloid, a slow burning colloid surrounding said quick burning colloid, and a cap of slow burning colloid secured to each end of said kernel.

7. As a new article of manufacture, a propellant kernel having a central perforated slow burning colloid, a quick burning colloid surrounding said slow burning colloid, a slow burning colloid surrounding said quick burning colloid and the whole protected at each end by a closure of slow burning substance, to retard the rate of burning at the ends.

8. As a new article of manufacture, a multiple propellant kernel composed of a plurality of single kernels compressed together, each being composed of colloids having different rates of burning arranged in layers, whereby the quicker burning colloids will be protected from the flame until the slower burning colloids have burned away.

9. As a new article of manufacture, a multiple propellant kernel, composed of a plurality of single perforated kernels, each comprising a plurality of layers of colloids having different rates of burning, said layers being so disposed that those forming the exterior surface of the kernel and the interior

surface of the perforation are slowest burning and successive layers from such surfaces toward the center of the web of the kernel being composed of a more rapid burning colloid than the one which envelops it.

10. As a new article of manufacture, a multiple propellant kernel composed of a plurality of single perforated kernels, each comprising a plurality of layers of colloids having different rates of burning, said layers being so disposed that those forming the exterior surface of the kernel and the interior surface of the perforation are slowest burning and each successive layer from such surfaces toward the center of the web of the kernel being composed of a more rapid colloid than the one which envelops it and the whole protected at the ends from the flame by the application of a slow burning substance to retard the rate of burning at the ends.

11. As a new article of manufacture, a multiple propellant kernel having an outer jacket of slow burning colloid and a plurality of single perforated kernels within said jacket, each comprising a quick burning colloid protected on its exposed surfaces by one or more layers of slow burning colloids, so disposed that each layer of slower burning colloid surrounds one which is quicker burning than itself.

In testimony whereof, I have hereunto set my hand in the presence of two witnesses.

CHAS. NEWTON.
